UNITED STATES PATENT OFFICE.

FRANK ROBINSON AND PERCY W. J. LANDER, OF BANGOR, MAINE.

TROLLEY-SUPPORT FOR ELECTRIC CARS.

SPECIFICATION forming part of Letters Patent No. 449,886, dated April 7, 1891.

Application filed January 12, 1891. Serial No. 377,421. (No model.)

To all whom it may concern:

Be it known that we, FRANK ROBINSON and PERCY W. J. LANDER, citizens of the United States, residing at Bangor, in the county of Penobscot and State of Maine, have invented certain new and useful Improvements in the Trolley System for Electric Street-Cars; and we do hereby declare that the following is a full, clear, and exact description of our invention, that will enable others skilled in the art to which it appertains to make and use the same.

Our invention relates to improvements in the trolley system for electric street-cars; and it consists of an automatic-operating trolley-arm connector, which is illustrated in the accompanying drawings, forming part of this specification, in which—

Figure 1 represents a side elevation, partly in section, of our invention, showing the trolley-arm in working position and connection with the car-standard. Fig. 2 shows a similar view of our device with the tension-spring released and the trolley-arm resting in a horizontal position. Fig. 3 is a side elevation of our invention, partly in section, showing a portion of the trolley-arm in an elevated position and the car-standard located between the tension-spring and operating mechanism. Fig. 4 is a similar view of the construction shown in Fig. 3, showing manner of setting the tension-spring with the trolley-arm. Fig. 5 represents a side elevation of the tension-rod of our invention, showing relative position of catch and trip-rod. Fig. 6 shows a perspective view of catch and trip-rod attached. Fig. 7 is a perspective view of the tension-rod foot shown attached to a portion of the tension-rod.

Similar letters of reference refer to correspondingly-like parts throughout the several figures.

A serious impediment to electric railroading, where the trolley system is used, is the jumping of the trolley from the overhead-current wire. This is attended many times with great danger, and is caused by numerous imperfections—such as bends, imperfect hanger-connections, switches, ice, &c.—upon the current-wire over which the trolley is obliged to travel; also, sudden jars and irregularities in the track cause the same results. As the

trolley is extended from a long pole, called a "trolley-arm," which is hinged near its opposite end to a connector with the top of the 55 car, and, furthermore, has its remaining extremity attached to a spring of sufficient strength to raise and hold the trolley against the current-wire, the tension of the said spring, together with a groove in the trolley, is all 60 that prevents the latter from disconnecting with the overhead wire. Thus when the car is traveling at speed, and especially when running over irregularities in the track and rounding curves, the jar occasioned by these 65 sudden changes is sufficient to cause a reaction of the tension-spring and a consequent rebounding of the trolley from the said current-wire. When such instances occur, no notice whatever is given to the car-driver. 70 The consequence is that before the momentum of the car can be checked the trolley-arm, now projecting in a vertical direction and being quite rigidly held there, has come in contact with the suspending cross-wires with sufficient force to either break the said arm, 75 wrench it from its fastenings, or tear down the cross-wires, so as to cause great danger by grounding the current, disabling the car, and necessitating a trip to the repair-shop. 80

It is therefore the object of our invention to prevent the possibility of such dangerous accidents occurring by producing an improved trolley-arm operator and connector so constructed that it will, when the trolley 85 leaves the current-wire, automatically release the tension-spring and cause the trolley-arm to immediately drop by its own weight into a horizontal position below possible interference with cross suspending-wires. 90

Referring to the drawings, A represents the usual post or standard rising from a flanged base B, which is attached to the top of an electric car. Upon this standard A and connecting the trolley-arm thereto is our invention, consisting of a vertical tube or casting G, having right-angular projections k and k' extending from its ends. Through these projections or castings k and k' are drilled transverse holes, through which the car-standard 95 A passes, and is secured thereto by means of collars c c, fastened in the usual manner by set-screws. The upper projecting casting k of our device is formed with an arm h rising

therefrom, the extremity of which is provided with means to hinge the usual trolley-arm thereto. Within this arm *h* of the upper casting *k* is drilled a small hole, through which a 5 trip-rod *l* passes and projects slightly. This trip-rod *l* branches at its opposite end to extend each side of a rod projecting out of the tube *G*, and is attached to a catch *t*, adapted to engage a notch or small shoulder upon this 10 protruding rod, as will hereinafter be described.

Extending through the tube *G* and constructed a sufficient length to extend beyond each end of the same is a rod *I*, called a "tension-rod," the lower end of which is formed at a right angle or may be provided with a right-angular projecting casting or foot *f*, rigidly fastened thereto, the said foot being provided with means at its extremity to connect 20 the lower end of the usual tension-spring *S* thereto. Near the upper end of the tension-rod *I* is a small notch or a shoulder *e*, into which the catch *t*, hereinbefore described, engages to prevent the said tension-rod from 25 being drawn farther upward through the tube *G*.

The trolley-arm as usually constructed consists of a pole about twelve feet in length provided with the trolley *F*, attached to one 30 end and fastened at its opposite end into a metal socket *D*, having a fan-shaped extension *n*. The socket *D* of the trolley-arm is hinged in the usual manner to the extremity of the arm *h* of the upper casting *k* of our 35 device, and the fan-shaped extension *n* extends beyond and above the hinged connection, as shown in Figs. 1, 2, 3, and 4 of the drawings. Attached to and extending over the periphery of the fan-shaped extension of 40 the trolley-arm is a metal strap *E*, which has its remaining end connected with the upper end of the tension-spring *S*, while the lower end of said spring is attached to the end of the projecting foot *f* of the tension-rod *I*. 45 The length of the tension-spring *S* should be such that when the tension-rod *I* is pushed down sufficiently to be held by the engagement of the catch *t* above the shoulder *e* thereon the said spring will have sufficient 50 strength to raise the trolley-rod into a vertical position. It can now be readily understood that the trolley-arm will be operated by the tension of the spring *S* in the usual manner; but in case the trolley *F* should leave 55 the current-wire by any means whatever, while the spring *S* would naturally throw the trolley-arm into the air before the said arm would reach a vertical position, its opposite end would strike the end of the trip-rod *l* 60 with sufficient force to disengage the catch *t* from the tension-rod *I*, and the tension-spring *S* would thus be released and draw the tension-rod *I* upward. When this sudden relaxation was felt by the trolley-arm, the latter 65 would be checked in its upward flight and immediately drop downward by its own weight, descending by the force of gravity

until it rested upon the now extending upper end of the tension-rod *I* in a horizontal position, as shown in Fig. 2 of the drawings. Our device can now be reset from the car-plateform by simply pulling down the trolley end of the trolley-arm by means of the usual cord there attached into the position shown in Fig. 4 of the drawings. This movement will force 75 down the tension-rod *I* until the catch *t* again engages the shoulder *e* upon the same, and the forcing down of the tension-rod must necessarily set the tension-spring *S*, for the latter is thereunto attached. This construction 80 leaves the tension-spring entirely free to exert all its energy upon the trolley-rod for the purpose of holding the trolley against the current-wire, and no extra power is required to set the device when tripped, for no extra 85 springs are used; neither are they strained beyond their usual working limit.

The catch *t* automatically engages the notch or shoulder in the tension-rod *I* by means of a small spring attached in any good and sufficient manner. In the drawings we have shown a flat spring *i* passing upward through a hole in the upper casting *k* and entering a notch in the said catch, thus limiting the distance of travel and preventing the catch from 90 being driven out of its fastenings and guides. The length of the trip-rod *l* can readily be adjusted by using a threaded thimble *l'* and turning it upon the threaded end of the said rod, as shown in Fig. 6 of the drawings. 95

In Figs. 3 and 4 of the drawings we have shown our device constructed to admit the car-standard *A* between the tension-spring and operating mechanism or tube *G*. This construction requires the tension-rod foot *f* to 100 be cast somewhat longer and with a hole therein adapted to allow the standard *A* to pass therethrough, and upon which it would slide. By using this construction a little 105 longer fulcrum upon the trolley-arm is obtained and a consequent greater strain and throw of the tension-spring. 110

Having thus described our invention, what we claim, and desire to secure by Letters Patent of the United States, is—

1. An automatic-operating trolley-arm connector consisting of a vertical tube, having projections at each end provided with means for attachment to the ordinary electric-car standard, the upper projections having an arm extending therefrom, with its extremity adapted to be hinged to a trolley-arm, a tension-rod extending through said vertical tube and having its lower end provided with means for connecting the tension-spring and the upper portion of said tension-rod having a notch or small shoulder for the engagement of a confining-catch, a catch adapted to engage the notch or shoulder in the tension-rod, and a trip-rod connected to said catch and extending in such manner that certain movements of the trolley-arm disengage said catch, substantially in the manner and for the purpose set forth and described. 115 120 125 130 135

2. In combination with a trolley-arm, operating-spring, and electric-car standard, an improved connector and trolley-operator consisting of a tube G, extending parallel with the car-standard and provided with means to be connected thereto, a tension-rod adapted to slide in said tube, said rod having its lower end or foot adapted to engage the lower end of the trolley tension-spring, a catch adapted to lock the tension-rod, and a tripping-rod connected to said catch, and means for hing-
- ing the trolley-arm in such manner that certain movements of the said arm disengage the catch and release the tension-spring, for the purpose described, and to operate substantially in the manner described.
